AIR-METHOD CLEANING AND DUSTING
TOOL

Daniel Benson Reogle, Berkeley, Calif., assignor to Citizens Trust Company, Toledo, Ohio, a corporation of Ohio, as trustee

Application July 24, 1930, Serial No. 470,511

24 Claims. (Cl. 15—155)

The invention relates to cleaning and dusting tools, and more particularly to pneumatic suction cleaning tools of the type known commercially under the registered trade-mark "Air-Way".
5 Such tools are adapted to be attached to the ends of pipes used in connection with either stationary or portable pneumatic cleaning machines, and more particularly in connection with apparatus of the type illustrated in my Patent 1,533,271, dated 10 April 14, 1925.
The present application is in the nature of an improvement on the device disclosed in my prior Patent 1,403,524, dated January 17, 1922. In common with the cleaning tool covered by this 15 patent, the present invention relates to a suction tool, having a body composed of resilient elastic material, which body portion includes a shank having a portion thereof shaped and adapted to be connected at one end to a suitable suction 20 pipe or nozzle, as shown in my Patent 1,533,271, and having at its other end a mouth portion which may be used directly for cleaning or dusting purposes, but which is adapted to receive a dusting or application member of suitable construction.
25 The cleaning tool is provided with a passage-way which opens into the shank portion and which is provided with a reduced throat portion connecting the mouth and the shank portions thereof. It has been found in practice that when excessive pressure is applied to the tool during 30 use, there is a tendency for the rubber shank to collapse or bend at this reduced portion, and according to the present invention, this defect is overcome by providing a reinforcing rib or ridge 35 extending longitudinally of the shank to compensate for the reduced portion.

Another feature of the present invention is the shape of the rubber end of the shank which is placed over the suction tube of the cleaning 40 apparatus. This tube or nozzle, as disclosed in my prior Patents 1,403,524 and 1,533,271, may be either round or flat. According to the present invention the end of the shank which is applied to the suction tube is normally oval-shaped, and 45 consequently fits readily over a round or flat tube, the material of which the shank is made being sufficiently deformable for this purpose.
Another feature of the present invention is the provision of a pocket in the mouth of the body 50 member, which pocket is provided with resilient walls or ribs which when forced apart and the application member forced therein grip the application member sufficiently tightly to detachably retain the same within the mouth. As to 55 this feature the present application contains mat-

ter in common with my application Serial No. 15,529, filed March 14, 1925.

The novel form of the dusting tool constitutes another feature of the invention. Other features will appear hereinafter. 5

The invention will be more readily understood by reference to the accompanying drawings and the following detailed description, setting forth a specific embodiment of the invention.

In the drawings:

Fig. 1 is a perspective view illustrating one form of the tool in use, the tool being applied to a round suction pipe, and the application member comprising a hollow element of substantially frusto-conical form to the mouth of which a soft 15 fabric cover is applied;

Fig. 2 is a side elevation of the tool with the body and application members assembled ready for use;

Fig. 3 is a longitudinal cross-sectional view of 20 the body member;

Fig. 4 is a transverse section on line 4—4 of Fig. 2;

Fig. 5 is a view looking into that end of the rubber shank of the tool to which the suction 25 pipe is to be applied;

Fig. 6 is a perspective detail view of the application member, shown in assembled position in Figs. 1 and 2, the mesh cover being removed;

Fig. 7 is an axial sectional view of the same; 30

Fig. 8 is a perspective view of the silken netting or fabric cover which is adapted to be assembled with the application member shown in Figs. 6 and 7;

Referring particularly to Fig. 1, A denotes a 35 suction pipe or tube of any desired type, but preferably one of the detachable extension members of a cleaning apparatus such as is shown in my Patent 1,533,271, and B the hollow body portion of an application tool, which is detachably connected to the suction pipe. At the mouth of the body member an application member C is detachably applied. For the purpose of illustration the tool is shown in use for removing dust from a cushion D. 40

The hollow body B of the application tool is made of resilient elastic material, preferably rubber, and comprises a shank portion 10, to the end 11 of which the suction pipe A is applied, 50 and a mouth portion 12 connected to the shank through an intermediate throat portion 13. As shown, the axes of the shank and mouth portions are substantially at right angles to each other.

The shank 10 is preferably provided with a 55

strengthening bead or lip 14, at the end of which the handle is applied, and as shown in Fig. 5, its end is neither round nor flat, but oval, thus permitting the shank to be readily applied to either a round or flat suction pipe. A round pipe A is shown in Fig. 1, but the same shank conforms itself equally as well to a flat tube or nozzle, such as that disclosed in my prior Patent No. 1,403,524, due to the resilience and elasticity of the material of which it is composed. The stiffening bead or lip 14 insures an air-tight fit.

Since pressure must be applied to the pipe A when the tool is in use, there was a tendency in the device disclosed in my patent for the shank to bend or collapse. The collapsing tendency was increased by the suction within the tool. To avoid this tendency I have, according to the present embodiment of the invention, provided a strengthening rib 15, herein shown as extending longitudinally along the upper surface of the shank, and being of greatest thickness adjacent the throat of the tool. This rib effectively overcomes the bending or collapsing tendency of the shank.

As shown, the mouth 12 of the body member of the tool is provided with two inwardly projecting ribs or walls 16, 17, between which is formed an annular groove or pocket 18 designed to receive a corresponding flange or bead 20 on the hollow frusto-conical element 21 of the application member C. An external rib or bead 19 extends around the lower portion of the mouth 12 for strengthening purposes. The ribs or walls 16-17 of the pocket 18, when forced apart by the insertion of the bead or flange 20, will firmly but detachably grip the bead and prevent accidental removal or loss of the application member.

As shown in Figs. 1, 2, 6, 7 and 8, the application member includes the hollow element 21 substantially frusto-conical in form, preferably composed of phenolic condensation product, fiber or other similar material, provided with the bead 20 at the upper portion for cooperation with the groove 18 in the body B, as above described, and provided also with a lower flaring skirt portion, preferably reinforced at intervals by suitable strengthening ribs 22. A bead 23 is formed at the lower extremity of the skirt.

A fabric mesh cover 24, shown in detail in Fig. 8, is then applied to the conical member. The cover provides a soft, flexible, porous under-surface, which engages furniture or other articles being cleaned without marring the same, and permitting fine particles of dust to pass through the mesh of the fabric, while preventing passage of larger particles. Such a cover renders the tool useful in cleaning smooth surfaces, as well as for cleaning small articles which might be drawn into the suction handle were it not for the fine mesh cover, which cover acts as a filter. The cover may be composed of any suitable mesh material, depending on the size particles it is desired to have pass therethrough. Preferably material of soft, silken texture is employed. The cover is readily attached to the conical member 21 by drawing the mouth of the cover over the bead 23 and detachably securing the parts together by any suitable means, as a rubber elastic band 25.

The invention has been described in detail for the purpose of illustration, but it will be apparent that many modifications may be resorted to without departing from the spirit of the invention.

It will be apparent that the body member of the tool, shown in Fig. 3, may be used for clean-

ing purposes without the additional application member, the bead 19 serving for attachment of a mesh fabric hood if desired. Furthermore, other application members than that specifically disclosed herein may be used in conjunction with the body member, other forms particularly adapted for this purpose being disclosed in my companion application Serial No. 550,786, filed July 14, 1931.

What is claimed is:

1. In a suction cleaner of the character described, an open-mouthed rubber application head, an annular groove in said application head opening into the interior thereof, a pair of spaced annular ribs integral with said application head forming the walls of said groove, said ribs constraining toward each other when forced apart, and an application member comprising a skirt having a peripheral bead adapted to be forced into said grooved and detachably held by said resilient walls.

2. In a suction cleaner of the character described, an open-mouthed elastic rubber application head, an internal groove in said application head opening into the throat thereof having spaced annular resilient integral walls comprising ribs constraining toward each other when forced apart, and an application member comprising a skirt having a peripheral bead adapted to be forced into said groove in said application head and detachably held by said resilient ribs, said bead extending externally only of said skirt portion.

3. An application member mounting for a suction cleaner dusting tool, comprising a body of resilient material having a passageway therethrough, said body formed with a portion opening into said passageway adapted to engage a removable suction tube and with an annular pocket opening into said passageway forming a seat, parallelly extending spaced integral walls in said body defining said seat, an application member having a peripheral bead extending externally only and adapted to be positioned in said seat, and a flaring skirt projecting beyond the body member.

4. A suction cleaning tool comprising an elastic rubber body with contractible open ends, one end for securing it to the open end of a suction tube and the other end having a pair of like continuous internal ribs separated by an interior peripheral groove, an open-centered application member having a peripheral flange at one end thereof extending externally only and adapted for engagement within said peripheral groove, and an outwardly flaring skirt projecting beyond the body member.

5. A suction cleaning tool comprising an elastic rubber body with contractible open ends, one end for securing it to the open end of a suction tube, and the other end having a pair of like internal ribs separated by an interior peripheral groove, and an application member comprising a flaring skirt having a peripheral bead extending externally only of said skirt and adapted for engagement within said peripheral groove.

6. A suction cleaning tool comprising an elastic rubber body with contractible open ends, one end serving for attachment to the open end of a suction tool, and the other having a pair of like internal ribs separated by an interior groove, a portion of said body extending below the lower of said internal ribs, an external reinforcing rib at the lower edge of said downwardly extending portion, and an application member having a

bead extending externally only and a flaring skirt portion extending beyond the reinforcing rib of said body member.

7. A suction cleaning tool comprising a resilient rubber body including a hollow shank portion of normally oval cross section adapted to be connected to a suction pipe, and a hollow head portion having a mouth facing at an angle to the shank, a restricted neck portion connecting the shank and head portions of the tool, and an external rib extending along the shank and neck portions on the side opposite the mouth, said rib being of greatest thickness adjacent the narrowest portion of the neck.

15 8. A suction cleaning tool comprising a resilient rubber body member, including a shank portion adapted to be connected to a suction handle, a mouth portion substantially at right angles to the shank portion for securing an application element, a narrow throat connecting said shank and mouth portions, and a longitudinal rib on the exterior of said shank portion on the side opposite the mouth, said rib being thickest adjacent the narrow throat portion of the tool, whereby binding or collapsing of the shank on application of pressure to the tool when in use is prevented.

30 9. A suction cleaning tool comprising a resilient rubber body member having a hollow shank adapted to be detachably secured to a suction pipe, a portion of said body being bent at an angle to form a head portion, and a restricted neck at the juncture between the shank and head portions, there being a reduced portion on the exterior of said shank to form the neck and a longitudinally extending external reinforcing rib on the side of the shank opposite the reduced portion, said rib being thickest adjacent the reduced portion to prevent collapsing of the shank on the application of pressure to the tool.

40 10. A suction cleaning tool comprising a hollow elastic rubber body with contractible open ends, one end serving for attachment to a suction tube, and the other end comprising a mouth portion having a pair of internal ribs separated by a groove, and an application member adapted to be detachably secured thereto, having an external bead adapted to fit within the groove in said mouth portion and comprising a skirt portion flaring outwardly beyond said bead, said body member having a flaring portion extending below the lower of said internal ribs for engagement with the flaring surface of said application member.

55 11. A suction cleaning tool comprising a hollow body including a shank portion adapted to be detachably secured to a suction handle, a hollow application member communicating with said body and extending at an angle to said shank, said application member including a skirt flaring outwardly and having an external bead at the expanded end thereof, and a mesh fabric hood secured over said bead and covering the expanded end of the application portion of the tool.

65 12. A suction tool comprising a hollow resilient body having an internally grooved mouth portion and an application member adapted to be detachably secured thereto, said application member having an exterior bead adapted to fit within the groove in said mouth, and including a skirt portion flaring outwardly below said bead, a mesh cover having its limit edges secured to a continuous elastic band, said band holding the cover in direct contact with the application end of said member.

13. A suction cleaning tool comprising a hollow flexible body member having a shank adapted to be detachably secured to a suction handle and a mouth at the opposite end thereof having an annular internal groove, and an application member having a bead for engagement with said groove, said application member having a skirt portion flaring outwardly below said bead.

5 14. An application tool comprising a hollow body including a flaring skirt portion having a mouth at the enlarged end thereof, an external bead surrounding said mouth, and a cover for said enlarged end comprising a soft mesh fabric hood retained in direct contact with the margins of the mouth of said tool, said cover having a neck portion fitting closely over said external bead, and means detachably retaining said cover in position.

10 15. An application tool comprising a hollow body including a flaring skirt portion having an annular external bead surrounding the enlarged open end of the tool, and a cover for said enlarged end comprising a mesh fabric hood retained in direct contact with the margin of said open end, a neck portion of said cover extending over said bead, and a continuous elastic band secured to said neck for detachably retaining said cover in position.

20 16. An application tool for suction cleaners, comprising a hollow body of generally frusto-conical form, having a flaring skirt portion, the interior of which is convexly curved, and an external annular bead at the larger end of the tool, a soft mesh fabric cover for the end of the tool, and elastic means retaining the edges 30 of said cover over said bead.

35 17. An application tool for suction cleaners, comprising a hollow body of generally frusto-conical form, having a flaring skirt portion, the interior of which is convexly curved, said skirt 40 having correspondingly curved reinforcing ribs extending intermediate the ends of the tool.

45 18. An application tool for suction cleaners, comprising a hollow body of generally frusto-conical form, having a flaring skirt portion, the interior of which is convexly curved, said skirt having correspondingly curved reinforcing ribs extending intermediate the ends of the tool, and a pair of annular external beads, one adjacent each end of the tool.

50 19. An application tool for suction cleaners, comprising a hollow body having a flaring skirt, a pair of annular beads one adjacent each open end of the tool, and reinforcing ribs for said skirt member extending intermediate the beads. 55

20. A suction cleaning tool comprising a hollow flexible body member having a shank adapted to be detachably secured to a suction handle, a portion of said body extending at an angle to said shank and provided with a mouth, an annular groove being formed in said mouth, and an application member having a bead for engagement within said groove, said application member having a skirt portion flaring outwardly below said bead.

60 21. An application element for the mouth of a cleaning tool comprising a hollow body of substantially frusto-conical form, an attachment flange adapted to secure it at its smaller end to the mouth of a suction tool, an external bead 70 formed on the larger end of the tool, and a hood made of soft mesh fabric fitting over and covering the larger beaded end, and serving as a filter over the face of said tool.

65 22. A suction cleaning tool comprising a hol- 75

- low flexible body member having a shank adapted to be detachably secured to a suction handle, a portion of said body extending at an angle to said shank and provided with a mouth, an annular groove being formed in said mouth, an application member having a bead for engagement within said groove, said application member having a skirt portion flaring outwardly below said bead, and a mesh fabric secured at the lower end of said skirt portion.
- 10 23. In a suction cleaning tool comprising a body portion having an internally grooved mouth, an application member, said application member comprising a hollow body of substantially frusto-conical form having an annular bead at the upper portion thereof for engagement with said grooved mouth, a skirt flaring downwardly
- 15

and outwardly below the beaded portion and a soft fabric mesh cover for the lower opening, detachably secured to the skirt member.

24. A suction tool comprising a hollow resilient body having an internally grooved mouth portion and an application member adapted to be detachably secured thereto, said application member having an exterior bead adapted to fit with the groove in said mouth, and an external reinforcing bead on said body member below 10 said internal groove, said application member comprising a skirt portion flaring downwardly below said bead, and having flaring, reinforcing ribs, and a mesh cover for the application end of said application member.
